VENDOR'S VEHICLE

Celestino H. Amaral, Hartford, Conn.

Application February 11, 1950, Serial No. 7,896

Term of patent 7 years

(Cl. D14—3)

To all whom it may concern:

Be it known that I, Celestino H. Amaral, a citizen of the United States of America, residing at Hartford, in the county of Hartford and State of Connecticut, have invented a new, original, and ornamental Design for Vendor's Vehicle, of which the following is a specification, reference being had to the accompanying drawing, forming part thereof.

Fig. 1 is a plan view of a vendor's vehicle embodying my novel design.

Fig. 2 is a side elevational view thereof.

Fig. 3 is a rear end view thereof.

Fig. 4 is a front end view thereof.

I claim:

The ornamental design for a vendor's vehicle, substantially as shown.

CELESTINO H. AMARAL.
